INVENTOR

Maurice B. Johnson.

BY J. F. Ebert

ATTORNEY

UNITED STATES PATENT OFFICE.

MAURICE BERNAYS JOHNSON, OF NEWARK, NEW JERSEY.

PAPER-FILE.

1,342,504.

Specification of Letters Patent.

Patented June 8, 1920.

Application filed December 5, 1919. Serial No. 342,783.

To all whom it may concern:

Be it known that I, MAURICE BERNAYS JOHNSON, a citizen of the United States, residing in Newark, in the county of Essex and State of New Jersey, have invented certain new and useful Improvements in Paper-Files, of which the following is a full, clear, concise, and exact description.

This invention relates to a paper file of 10 the character usually kept on a desk, table or like convenient place, and has for one of its objects the provision of a file of this type upon which papers may be conveniently inserted or removed.

15 Another object of the invention is the provision of a clasping member, which is adapted to instantaneously free all of the papers on the file.

20 A special object of the invention is providing a file upon which papers may be quickly and securely placed with the use of one hand and at the expense of a minimum of energy.

25 Other objects of the invention have to do with various features of construction and arrangement of parts hereinafter set forth and defined by the appended claims.

30 In accordance with this invention there is provided a back or baseboard having secured upon one side thereof resilient members which normally effect the engagement

35 of a U-shaped clasping member with the opposite surface of the baseboard near one edge thereof. The U-shaped clasping member is reciprocally mounted so that the portion intermediate the leg portions clears the edge of the baseboard adjacent thereto in the filing of papers. This is accomplished

40 by giving each of the leg portions of the clasping member a plurality of contours and confining certain of the curved sections in guide members adapted to direct the closed end of the U-shaped member upwardly and outwardly. The clasping member may be

45 raised by either exerting pressure on the baseboard or by means of suitable grips. When the clasp is reciprocated the full length of its stroke in an upward direction, the base thereof completely clears the normal

50 projecting edge of the baseboard, and, when released, moves toward the adjacent surface of the baseboard until arrested thereby or by papers resting thereon. The tension of the resilient members for functioning the

55 clasp is sufficient to maintain any papers held thereunder firmly in place.

The nature of the means by which the foregoing and other specific objects of the invention are accomplished will appear from the following detailed description. 60

Referring to the drawings,

Figure 1 is a perspective of the file contemplated by this invention;

Fig. 2 is a rear elevation thereof showing the clasping member disengaged; and 65

Fig. 3 is a perspective showing the means for attaching the resilient members for functioning the clasp of the baseboard.

The file shown in the drawings is comprised of a baseboard 1 having secured on 70 the back thereof a pair of resilient members 2 consisting preferably of flat spring metal. Each of the resilient members 2 has one of its ends held in a socket member 3 designed to provide a fulcrum when the said resilient members are moved toward the opposing surface of the baseboard, thereby furnishing a means for maintaining the said members constantly under tension which may be automatically increased as hereinafter more 75 fully explained. The socket members 2 are each provided with extensions 4 having an aperture adapted to accommodate a screw, and may be fastened together by a connecting link 5, said link and socket members 85 being preferably of cast iron and constituting a single casting.

The resilient members 2 are connected at their free ends by a cross arm 6 held in position by means of screws 7, each of which 90 has a seat in the respective bracket members 8. Each of the bracket members 8 has a seat for receiving the cross-arm 6, and their upper ends are provided with depressions adapted to form bearings 9, in 95 conjunction with the upper ends of the resilient members 2, which ends are arranged to fit flush with the edges of the said bracket members. The bearings 9 are adapted to accommodate off-set portions on the open 100 ends of the U-shaped clasping member 10. The several leg portions of the clasping member 10 are given a plurality of off-sets, curvatures and inclinations so as to produce a configuration substantially as shown, and cause the closed end portion 12 of the said 105 clasping member to normally engage the opposite or outer surface of the baseboard adjacent the upper edge thereof. This engagement is effected by placing the resilient members 2 under tension, which may be easily accomplished by virtue of the con-

struction of the socket members 3. The normal tension of the resilient members 2 is automatically increased as the closed portion 12 of the clasping member 10 is moved 5 away from the baseboard. This latter feature is of advantage when a considerable number of papers are filed, the increased tension on the clasping member firmly holding them in position.

10 The inclined portions of the clasping member 10 are adapted to be confined within guide members 13 integrally formed on the extremities of a gripping plate 14 secured near the upper edge of the baseboard 1. The 15 guide members 13 are adapted to give considerable latitude to the movement of the arms of the clasping member 10 when the latter is reciprocated in a forward and backward direction. This is accomplished 20 by providing the lateral contacting surface of the guide members 13 with suitable beveled or inclined faces so that, when the clasping member 10 is moved toward the baseboard 1, the closed portion 12 of said member will 25 be directed upwardly and outwardly in such manner as to entirely clear the normal projecting edge of the baseboard. It is, of course, to be appreciated that the contours of the arm portions of the clasping member 30 10 are also an important factor in effecting the result just described.

From the foregoing description the operation of the file contemplated by me is readily understood. The file, if kept upon a desk, 35 is placed with the upper surface of the baseboard exposed. When it is desired to file a paper all that is required is to place the paper on this exposed surface and by exerting a downward pressure, which may be 40 done with the same hand holding the paper, the clasping member 10 is moved upwardly and outwardly so as to clear the end of the paper intended to be filed. Having cleared the same, by removing the hand, the resilient 45 members 2 restore the clasping member 10 to normal position, thereby effecting the filing of the paper by firmly holding the same intermediate the closed portion 12 of the clasping member and the adjacent surface 50 of the baseboard 1. This operation is very simple and easily performed. In the event it is desired to remove a paper from the file the disengagement of the clasping member 10 is effected in a similar manner, thereby 55 simultaneously freeing all of the papers on the file, any of which may be taken out of the file and quickly replaced when desired.

As an additional means of opening and closing the clasping member 10, a second 60 gripping plate 15 is provided which is carried by the resilient members 2. By taking the plates 14 and 15 between the fingers and squeezing the same, the clasping member 10 may be opened and closed. This arrangement is of convenience where it is 65

wished to function the file when not resting upon an object such as a desk, table or the like.

From the above description, it is obvious that one of the salient features of my invention resides in the provision of a file which can be functioned with one hand and, at the same time, securely hold all papers desired to be filed without perforating the same. This is of considerable advantage 70 where the person using the file ordinarily has one hand engaged, as, for instance, a waiter on a dining car. With a file of this type, for instance, it is very easy for him to remove the menu with one hand while, 75 at the same time, he has the other hand engaged. Where the rapid filing of papers is desired, the same may be accomplished with a minimum of time and energy.

While this invention has been set forth 80 in a certain preferred embodiment, it will be understood that modifications may be made without departing from the spirit and scope thereof.

What is claimed is:

1. A paper file comprising a baseboard, a reciprocally mounted clasping member secured to one surface of said baseboard and adapted to engage papers contacting with the opposite surface thereof, resilient means 95 for functioning said clasping member, said clasping member being substantially U-shaped and having the legs thereof provided with a plurality of contours, and a guide member for each of the legs of the said 100 clasping member, the relation of the legs of said clasping and guide members being such as to cause the clasping member to clear the edge normally projecting intermediate the mounting and the closed end of said clasping member.

2. A paper file comprising a baseboard, a reciprocally mounted clasping member secured to one surface thereof and adapted to engage papers contacting with the opposite 110 surface of the said baseboard, and means for reciprocating the clasping member in such a manner as to cause it to clear the end of the baseboard.

3. A paper file comprising a baseboard, 115 and a clasping member reciprocally mounted thereon, said clasping member being adapted to clear the edge of the filing surface of the baseboard during the filing of papers.

4. A paper file comprising a baseboard and a clasping member reciprocally mounted thereon, the said member when moved the full length of its stroke in an upward direction completely clearing the normally 125 projecting edge of the baseboard.

In testimony whereof, I have hereunto subscribed my name this fourth day of December 1919.

MAURICE BERNAYS JOHNSON.
